(57) **CLAIM**

The ornamental design for a bottle filler, as shown and described.

DESCRIPTION

FIG. 1 is a perspective view of a bottle filler showing my new design;

FIG. 2 is a front elevational view thereof;

FIG. 3 is a top plan view thereof;

FIG. 4 is a right side elevational view thereof; and,

FIG. 5 is a left side elevational view thereof.

The back and bottom sides of the bottle filler are flat and unornamented.
